(57) **CLAIM**

We claim the ornamental design for a handrail, as shown and described.

DESCRIPTION

This application is a broadening reissue of U.S. Pat. No. D706,451 which issued Jun. 3, 2014 from application Ser. No. 29/462,252 filed Jul. 31, 2013.

Notice: More than one reissue application has been filed for the reissue of U.S. Pat. No. D706,451. The reissue applications are application Ser. No. 29/515,597 (the present application), and divisional application application Ser. No. 29/626,577 filed Nov. 17, 2017.

FIG. 1 is a perspective view of a handrail [ ] showing our new design;

FIG. 2 is a front elevation view of the handrail of FIG. 1 [ ]. The [ ], the opposing rear elevation view is a mirror image [of the illustrated view] thereof;

FIG. 3 is a top plan view of the handrail of FIG. 1 [ ].

FIG. 4 is a bottom plan view of the handrail of FIG. 1 [ ].

FIG. 5 is a left side elevation view of the handrail of FIG. 1; and,

FIG. 6 is a right side elevation view of the handrail of FIG. 1.

[In FIGS. 1-6, the] The broken lines [indicate environmental features and] in the drawings illustrate portions of the handrail that form no part of the claimed design.

1 Claim, 1 Drawing Sheet

Matter enclosed in heavy brackets [ ] appears in the original patent but forms no part of this reissue; matter printed in italics indicates the additions made by reissue.
